Primary Examiner — Sandra Snapp*Assistant Examiner* — Molly Loch(74) *Attorney, Agent, or Firm* — Fross, Zelnick, Lehrman & Zissu, P.C.; Charles T. J. Weigell, Esq.(57) **CLAIM**

The ornamental design for a table clock, as shown and described.

DESCRIPTION

FIG. 1 is a front perspective view of a table clock showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the table clock that form no part of the claimed design.
